(57) **CLAIM**

The ornamental design for a grapple bed, as shown and described.

DESCRIPTION

FIG. 1 is an isometric view of a grapple bed;

FIG. 2 is a close up view of Detail A of FIG. 1;

FIG. 3 is a front view of the grapple bed of FIG. 1;

FIG. 4 is a close up view of Section B-B of FIG. 1;

FIG. 5 is an interior isometric view towards the front of the grapple bed of FIG. 1;

FIG. 6 is a top view of a front end of the grapple bed of FIG. 1;

FIG. 7 is a rear view of the grapple bed of FIG. 1;

FIG. 8 is a rear view of the grapple bed of FIG. 1 excluding view of the front end of the grapple bed;

FIG. 9 is an interior isometric view towards the rear of the grapple bed of FIG. 1;

FIG. 10 is an interior view towards the rear of the grapple bed of FIG. 1;

FIG. 11 is a top view of a rear end of the grapple bed of FIG. 1;

FIG. 12 is a right side view of the grapple bed of FIG. 1;

FIG. 13 is a left side view of the grapple bed of FIG. 1;

FIG. 14 is a top view of the grapple bed of FIG. 1; and,

FIG. 15 is a bottom view of the grapple bed of FIG. 1.
